UNITED STATES PATENT OFFICE.

EDWIN L. BRUCE, JR., OF LITTLE ROCK, ARKANSAS.

BUNDLE PROTECTOR.

Application filed June 10, 1921. Serial No. 476,464.

To all whom it may concern:

Be it known that I, EDWIN L. BRUCE, Jr., a citizen of the United States, and a resident of Little Rock, in the county of Pulaski and 5 State of Arkansas, have invented a new and useful Improvement in Bundle Protectors, of which the following is a full, clear, and exact description.

My invention relates to bundle protectors, 10 and it consists in the combinations, constructions and arrangements herein described and claimed.

An object of my invention is to provide a simple, inexpensive and effective device that 15 can be readily applied to bundles of strips, or the like, at the ends thereof to protect the strips during the handling incidental to the shipment of the bundles.

A further object of my invention is to 20 provide a device of the character described that can be produced cheaply and readily and which may therefore be discarded with but slight loss when worn out in service.

A further object of my invention is to 25 provide a device adapted to be held in place at the end of a bundle by means serving also to bind the strips in the bundle together.

Other objects and advantages will appear 30 in the following specification, and the novel features of the invention will be particularly pointed out in the appended claims.

My invention is illustrated in the accompanying drawings, forming part of this application, in which—

35 Figure 1 is a view showing the use and application of the device,

Figure 2 is an enlarged perspective of the device, and

40 Figure 3 is an enlarged view of a blank used in forming the device.

In carrying out my invention, I make use of a sheet 1 of a suitable material, such as cardboard. The sheet 1, which has been cut to a predetermined size with the opposite 45 edges thereof straight and parallel, is folded along lines parallel with selected opposite edges thereof to closely fit the sides of a bundle 2 made up of a plurality of strips 3 of lumber or other material. The selected opposite edges referred to will then abut each other along their entire length and are held together by an adhesive strip 4. A slit 5 is made in the sheet 1 along each corner of the folded cardboard, and extends from the end 55 of the cardboard which projects beyond the adjacent end of the bundle to a plane paral-

lel with the end wall of the longest strip in the bundle, whereby abutting flaps 6—6 and abutting flaps 7—7 are provided, the flaps 7—7 being adapted to overlap the flaps 6—6 so that the ends of the strips 3 are covered and the extremities of the strips are encased in the box-like structure formed from the sheet 1 in the manner described. The flaps 6—6 and 7—7 are secured in the position 60 illustrated in Figure 2 by an adhesive strip 8 which is arranged to extend along the sides of the box-like structure, as best seen in Fig. 2. At each junction of adjacent sides of the box-like structure or protector, a notch 9 is 65 provided. These notches are preferably arranged in the same plane and adjacent to the open end of the protector. A wire 10 is passed around the protector in position to engage the strips 3 or the portions thereof 70 exposed by the notches 9. The wire 10 is tightened, as by twisting the ends thereof together and has the double function of holding the protector in place and of aiding in the binding of the strips 3 into the bundle. 75

From the foregoing description of the various parts of the device, the operation thereof may be readily understood. While I have described the manner in which the device may be formed of a single sheet of cardboard to fit a bundle of any size, it will be understood that in practice the protectors 80 will be made in "stock" sizes in advance of their application and the method of forming the same may vary considerably from that described without departing from the spirit and scope of the invention. It will be understood also that a protector will be arranged at each end of the bundle. The ends of the several strips in a bundle are usually 85 not flush with each other and in consequence the longer strips are usually split or broken at their ends as a result of the handling received while the bundles are being transported from place to place. When my improved protector is arranged at each end of a bundle, the ends of the strips in that bundle are effectively protected. The protectors are held in place by the same wires or other 90 flexible members that are employed to tie the strips together. After the shipment has been completed, the protectors may be removed and packed into a compact package for return to the shipper for further use or may be replaced at a slight cost. 95

110

I claim:

1. A device of the character described

comprising a casing adapted to snugly fit and cover the end of a bundle of wood strips or the like, said casing being formed with a double end formed by overlapped laterally bent portions of the side walls, and provided with an opening at each intersection of the side walls arranged to enter adjacent the open end of the casing, and a flexible member adapted to encircle the casing and contact and grip said strips through said openings, whereby said strips may be held in close proximity one to another and said casing retained in position.

5 10

comprising a single sheet of cardboard slitted and folded to form a casing open at one end and adapted to snugly fit a bundle of strips at an end thereof, said casing being provided with notches through the sheet at the lines of folding and adjacent to its open end, means for maintaining the sheet in folded position, and a flexible member adapted to encircle the casing and to engage the strips through the notches to bind the strips and to hold the casing in adjusted position

15 20 25

on the strips.

2. A device of the character described

EDWIN L. BRUCE, JR.
